UNITED STATES PATENT OFFICE

GEORGE B. MORRIS, OF BRADFORD, PENNSYLVANIA, ASSIGNOR TO BRADFORD MOTOR WORKS, OF BRADFORD, PENNSYLVANIA, A CORPORATION OF PENNSYLVANIA.

PLUNGER FITTING FOR DEEP WELL PUMPS

Application filed April 17, 1930. Serial No. 444,983.

This invention pertains to hydraulic pumps of the type used in oil and other deep wells, and relates more particularly to an improved form of reciprocating plunger and packing arrangement for such pumps.

Among the chief difficulties encountered in the operation of pumps of this character and especially those employed in oil wells, is the rapid wearing out of the cups or packing, or both. Because of the heavy loads under which these pumps operate, and the sand and other abrasive materials encountered in the wells, this wearing takes place rapidly. It has been the usual experience to have the cups or packing wear out so rapidly that it is necessary to withdraw the pump plungers from the wells for repairs at comparatively short intervals, and these operations consume a considerable amount of time and labor, and represent a complete loss. This, with the inefficiency in operation of the pump caused by wearing of the cups or packing, constitutes a material part of the cost of operation of most oil wells. The present invention has for its chief object lengthening the working life of the cups or packing of such pumps.

With such an end in view it is the primary object of the invention to provide a reciprocating plunger for use in pumps of the above described character which is equipped with a packing arrangement that is adapted to automatically adjust itself to constantly maintain a highly efficient leak-tight contact between the plunger and the pump cylinder in which it operates, from the time it is put in operation until the packing is practically completely worn away, and whereby the over-all operating efficiency of the pump is greatly increased and also the life of the packing.

An outstanding feature of the invention resides in the accomplishing of this object through the provision of means for intermittently subjecting the packing on the plunger to the head pressure of the liquid column above the pump and for permitting it to relax or expand between the applications of such pressure. This intermittent compressing and relaxing of the packing produces a pulsating

action therein which maintains it in a constantly flexible condition, and at the same time in intimate contact with the walls of the cylinder. This is a decided improvement over the continual application of the packing of a pressure of the nature of the head pressure in the well, as such a pressure is applied constantly, the packing during the whole operation of the pump stroke being in extreme frictional contact with the cylinder walls and wears out with unnecessary rapidity.

Another object is to further enhance the life of the packing and plunger by providing a trap to prevent sand and other abrasives deposited from the liquid columns above the pump from passing between the plunger and cylinder walls where it wears out the packing and plunger.

A further object is to provide a plunger of simple, sturdy construction, which in addition to being equipped with a novel highly efficient long life packing arrangement, is adapted to be quickly and easily taken apart and reassembled for cleaning and the making of repairs.

These and other objects will become more apparent when the following detailed description is read in conjunction with the accompanying drawings, of which Fig. 1 is a vertical sectional view taken through a plunger constructed in accordance with what is now considered to be the preferred form of the invention, showing it arranged in its associated cylinder; and Fig. 2 an elevational view of the same with the cylinder removed.

Referring now to the drawings, the invention is illustrated as comprising a plunger consisting of an inner body forming tube 1, having a coupling member 2 threaded on its upper end and held securely in place by means of a pin 3. A thread 4 formed on its lower end, carries a hollow valve chamber-forming member 5 in which a one-way ball type valve 6 is arranged. This valve rests on a seat 7, made of some suitably hard wear-resisting material and firmly secured in a hollow retaining member 8, which is screwed into the lower end of the chamber-forming member 5. A pin 9 is provided in chamber

80

member 5 above the ball 6 to prevent its obstructing the lower end of tube 1 when the valve is unseated.

Above the member 5 there is mounted a 5 comparatively long sleeve-like packing 11 which is adapted to make leak-tight engagement with the walls of the pump cylinder 12 in which the plunger reciprocates. This packing may be made in any desired form 10 and out of any suitable long wearing flexible material, but is preferably spirally wound, as illustrated in the drawings, with its lower end seated on a support 13 which is screwed onto the lower end of tube 1. To hold the 15 support 13 in place, member 5 may be screwed into lock-tight engagement therewith.

Unlike the lower end of packing 11, the upper end, instead of being anchored to tube 1, is allowed to move axially thereon. A follower 20 14 is loosely mounted on tube 1 and seated on the free end of packing 11. Above this follower there are arranged a plurality of similarly mounted upwardly turned packing cups 15 which are held in place and spaced 25 from one another by a plurality of loosely mounted spacer rings 16. To hold follower 14 against the free end of packing 11 and the packing cups in place, a coil spring 17 is inserted above the top spacer ring 16 with its 30 one end bearing against the spacer ring and its other against the lower end of the coupling member 2.

The upper portion of the plunger is made up of an outer tube 18 having an outer diameter substantially the same as the inside diameter of the pump cylinder 12. This tube is attached at its lower end to coupling 2 which is provided with an exterior thread 19 for its reception, and has a pump rod engaging 40 crown member 21 mounted on its upper end for attaching the plunger to the pump rods (not shown). There are two chief reasons for making tube 18 of substantial length, and of substantially the same diameter as cylinder 12; one is to prevent the pressure of the column of liquid above the pump constantly bearing against the packing cups 15, and hence constantly compressing the packing 11, and the other is to provide a sand trap for collecting the sand and other abrasive material deposited from the liquid column above the pump. The sand trap is formed by tube 18 and an inner tube 22, which constitutes an extension or body tube 1 and is mounted in 50 the upper end of coupling 2 with its upper end extending to near the top of tube 18. By this arrangement, a chamber 23 is provided between the two tubes 18 and 22 into which the sand can pass by way of the opening 24 in 55 crown 21 instead of piling up on the top of the plunger.

An important feature of the invention resides in the intermittent subjection of the packing 11 to the compressing effect of the 60 head pressure of the liquid column above the

pump for forcing it into engagement with the walls of the pump cylinder and plunger. This is accomplished by providing one or more openings or perforations 25 in tube 1 above the packing cups 15 so that the liquid pressure in tube 1 is communicated to the packing cups 15 and by them transmitted to follower 14 bearing on packing 11, and by providing a ball valve 26, held in place by a perforated cage 27, on the upper end of tube 22. This valve assists valve 6 in lifting the liquid column in the well when the plunger is raised, but its more particular purpose is to prevent the head pressure from being impressed upon the packing cups 15 and packing 11 on the up stroke of the pump. Hence the packing cups 15 are exposed to the head pressure of the liquid column upon the down stroke of the plunger only, which is when valve 26 is unseated.

As will be readily appreciated, due to the extreme depth below the surface of the ground at which such pumps are usually operated, the head pressure above the pump resulting therefrom produces a very substantial compressive effect upon the packing when the upper valve 26 is unseated, forcing it tightly against the walls of the plunger and pump cylinder. The spring 17 is made sufficiently strong to hold the packing 11 in an efficient operating contact with cylinder 12 on the upstroke of the plunger, but its effect on the packing is normally considerably less than that of the head pressure. Hence when the head pressure is shut off by the closing of valve 26 and the pressure in tube 1 reduced the packing is relieved and allowed to relax. The alternate compressing and relaxing of the packing on the alternate strokes of the plunger keeps the packing in a continually flexible condition so that it is relatively easily maintained in intimate contact with the pump cylinder, instead of being allowed to become hardened and incapable of being forced into such contact as it wears away, which is a condition common in such packings where they are subjected to a constant pressure.

In operating the plunger to remove liquid from a well, it is reciprocated up and down in the cylinder 12, which although not so shown in the drawings as it forms no part of the invention, is considerably longer than the plunger and is provided at its lower end with the usual standing valve and screen. With each downward stroke of the pump the plunger is forced through the liquid trapped in cylinder 12 by the lower standing valve. This unseats the valves 6 and 26 and the pressure of the liquid column above the pump is impressed by reason of the openings 25 in tube 1 upon the packing cups 15 which in turn force the upper end of packing 11 downward and its sides into engagement with the walls of the cylinder 12 and plunger

tube 1. When the plunger is raised, valves 6 and 26 close, causing the liquid column thereabove to be raised and a suction to be established below them, drawing a new supply of liquid into the cylinder. With the closing of the valve, the head pressure is shut off from the packing and it is thereby relieved of that pressure on the upstroke of the plunger. Over a complete cycle of operation 10 of the pump the main packing 11 is alternately exposed to and shut off from the head pressure in the well. The pulsating action produced in this manner upon the packing has the effect of keeping it in a continually 15 flexible condition whereby it is adapted to be at all times readily forced into efficient operating contact with the walls of the plunger and cylinder. In actual practice, this has been found to both considerably increase 20 the efficiency in operation of the plunger and materially extend the life of the packing.

According to the provisions of the patent statutes, I have explained the principle and 25 mode of operation of my invention, and have illustrated and described what I now consider to be its best embodiment. However, I desire to have it understood that, within the scope of the appended claims, the invention 30 may be practiced otherwise than as specifically illustrated and described.

I claim:

1. A reciprocating pump plunger comprising an inner body forming tube having an 35 opening in its side wall adjacent its upper end, a main flexible packing below said opening, said packing being anchored at its lower end and free at its upper, a loosely mounted follower seated on the upper end of said 40 packing, an upwardly turned packing cup above said follower, an outer tube of substantially the same diameter as said packing mounted on the upper end of said body tube, an extension of the inner body tube mounted 45 within and forming a sand trap with said outer tube, and a one-way valve mounted in the upper end of said extension.

2. A reciprocating pump plunger comprising an inner body forming tube, a comparatively long flexible packing mounted upon 50 said tube with its lower end anchored thereto and its upper end arranged for free movement thereon, a follower loosely mounted on said tube and seated upon the free end of said packing, an upwardly turned packing cup loosely mounted on said tube above said packing follower, an outer open ended tube of substantially the same outer diameter as the packing secured to the upper end of said body tube, an extension of said body tube mounted within said outer tube and adapted to form a sand trap therewith, a one-way valve mounted in said extension, and another 55 in the lower end of the body tube proper.

3. A reciprocating pump plunger com-

prising an inner body forming tube, a comparatively long flexible packing mounted upon said tube with its lower end anchored thereto and its upper end arranged for free movement thereon, a follower loosely mounted on said tube and seated upon the free end of said packing, an upwardly turned packing cup loosely mounted on said tube above said packing follower, a spring above said packing cup constantly urging said cup toward 75 said packing, a coupling member secured to the upper end of said body tube, an outer open ended tube substantially of the same outer diameter as the packing secured to the coupling member, a crown shaped pump rod 80 engaging member secured to the upper end of said outer tubing, an extension of said body tube mounted within said outer tube and also secured to said coupling member, and a one-way valve mounted in both the upper end of said extension and the lower end of said body tube.

4. A reciprocating pump plunger comprising an inner body forming tube having a plurality of openings in the side wall thereof 90 adjacent its upper end, a main flexible packing mounted on the tubing below said opening with its lower end rested upon a packing support securely attached to the tube, a packing follower loosely mounted upon the tube and seated upon the upper end of said packing, a plurality of upwardly turned packing cups loosely mounted above said follower, a spring above said packing cups arranged to constantly urge them toward said packing, 100 a coupling member secured to the upper end of said body tube, a comparatively long outer open ended tube of substantially the same diameter of the packing attached to said coupling member, a pump rod engaging crown member attached to said outer tube, an inner tube comprising an extension of the body tube secured to said coupling member and forming a sand trap with said outer tube, a one-way valve mounted in the upper end of 105 said body tube extension, and a similar valve mounted at the lower end of the body tube 110 itself.

5. A reciprocating pump plunger comprising an inner body forming tube having a plurality of openings in the side wall thereof 115 adjacent its upper end, a main flexible packing mounted on said tube below said openings and rested upon a packing support securely attached to the tube, a packing follower loosely mounted upon the tube and seated upon the upper end of said packing, a plurality of upwardly turned packing cups loosely mounted above said follower and spaced from each other by a plurality of similarly mounted spacer rings, a spring above the uppermost of said packing cups arranged to constantly urge said cups toward the upper end of the main packing, a coupling member secured to the upper end of said body 120 125 130

5 tube, a comparatively long outer open ended tube of substantially the same diameter of the main packing attached to said coupling member, a pump rod engaging crown member attached to the upper end of said outer tubes, an inner tube comprising an extension of the body tube also secured to said coupling member and forming a sand trap with said outer tube, a one-way valve mounted in the upper 10 end of said body tube extension, and a valve mechanism mounted on the lower end of said body tube, said mechanism comprising a tubular chamber forming member threaded onto the lower end of the body tube in locking 15 relation with said packing support, a hollow valve supporting member threaded into said chamber member, a valve seat in the upper end of said valve supporting member, a valve fitted in said seat, and a pin in said chamber 20 member limiting the upward movement of said valve.

In testimony whereof, I sign my name.
GEORGE B. MORRIS.
